J. G. VINCENT

HYDROCARBON MOTOR

Filed June 30, 1920

*Inventor;
Jesse G. Vincent,*

By Milton Sibbets Atty.

UNITED STATES PATENT OFFICE.

JESSE G. VINCENT, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed June 30, 1920. Serial No. 392,975.

To all whom it may concern:

Be it known that I, JESSE G. VINCENT, a citizen of the United States, and a resident of Detroit, Wayne County, State of Michigan, have invented certain new and useful Improvements in Hydrocarbon Motors, of which the following is a specification.

This invention relates to hydrocarbon motors, and particularly to means for forming the mixture therefor and delivering it thereto.

In the use of combustion devices for heating the mixture passing to the motor, where the mixture for the devices is taken from the carburetor, if the action of the carburetor is such that the mixture produced by it becomes rich when the motor idles for a short time, as is the case with some carburetors, and with most carburetors under certain adjustments, the mixture fed to the combustion devices becomes so rich that irregular action occurs and sometimes fouling of the combustion chamber results. The increased richness of the mixture would not be so serious a matter in the idling of the motor if the combustion device operated satisfactorily with that mixture, because in that case the heat from the combustion device would considerably aid in vaporizing the heavy mixture and thus facilitate distribution to the cylinders.

One of the objects of the present invention is to provide a construction of motor intake conduit, carburetor, and combustion device and connections which will assist in keeping the combustion device supplied with a good burning mixture even though the carburetor may "load" or collect condensed gasoline in its air chambers and thereby affect the richness of the mixture.

Another object of the invention is to provide means for withdrawing condensed fuel from a part of the carburetor where it may collect and carry the fuel around the combustion device and discharge it into the motor intake conduit.

Another object of the invention is to provide means for supplying from a single carburetor, suitable mixture for a combustion device and a somewhat richer mixture for the motor.

Other objects and advantages of the invention will appear from the following

description taken in connection with the drawing which forms a part of this specification, and in which the figure is a vertical sectional view, with parts in elevation, of a carburetor and combustion device and adjacent parts of the motor, built in accordance with this invention.

Referring to the drawing, 10 represents a cylinder block, which may comprise one or more cylinders, of a hydrocarbon motor, and 11 is a passage or conduit for carrying the combustible mixture to the cylinders 65 through the intake valves. 12 is a continuation of the intake conduit 11 and is shown as formed in a casting 13 which may be connected to the cylinder block 10 as by bolts 14. The casting 13 forms an elbow, 70 in the horizontal part of which is the conduit 12 and in the vertical part of which is a conduit or chamber 15 which is shown as forming the mixing chamber of a carburetor. Suitably arranged in the intake 75 conduit 11—12 is a throttle valve 16 which may be opened and closed by the operator by any suitable connections.

The principal elements of the carburetor illustrated herein are of the well-known 80 Packard construction and comprise a float chamber 17, a fuel nozzle 18 in communication therewith, a main air intake passage 19 communicating with a Venturi tube 20, and an auxiliary air intake passage 21 controlled 85 by a spring closed valve 22 and communicating with the mixing chamber 15 by a passage 23 around the Venturi tube 20.

Mounted upon, and in fact formed as an integral part of the elbow 13, is a combustion device 24 for heating the mixture passing to the motor. This device comprises a combustion chamber 25 shown as forming a partial jacket on the elbow, a spark plug 26 for igniting the mixture in the chamber, 90 an outlet passage 27 communicating with the intake conduit of the motor beyond the throttle valve 16, so that the combustion chamber is always subject to the suction of the motor, and an intake conduit 28 having 100 its inlet opening or port 29 in the mixing chamber 15 so that the combustion device will withdraw its mixture from the carburetor. The intake conduit 28 includes a small inlet passage 30 in a plug 31 and a 105 screen 32 assists in breaking up the mix-

ture as it passes into the combustion chamber. A glass window 33 is also provided for observing the burning of the mixture in the chamber.

From the above description, and without the additional means which is about to be described, it will be seen that whatever mixture is supplied to the motor by the carburetor, will also be supplied to the combustion device, which, under ordinary running conditions of the motor under load, is desirable. However, it is found that if the motor is idled for any length of time, some of the heavier particles of fuel will drop down around the Venturi tube 20 into the air passage 21 and collect there. A slight opening of the throttle will then cause the air valve 22 to open and much of the fuel collected in the air passage 21 will be drawn into the combustion device and into the motor, thus choking them both off. The present invention overcomes this by providing means for withdrawing the fuel collecting in the passage 21 and carrying it around the combustion device to the motor intake conduit beyond the throttle valve 16 so that while the motor may be supplied with a slightly richer mixture during such idling time, yet the combustion device will receive the normal mixture supplied by the carburetor and it will, therefore, function in the usual way and the hot burnt gas passing from it to the motor intake conduit through the passage 27 will greatly assist in vaporizing the heavy mixture and thereby assist the distribution of the mixture to the cylinders of the motor. This means, in the form shown, comprises a suction pipe or conduit extending from the bottom of the passage 21 to the motor intake conduit beyond the throttle valve. 34 is the pipe and it connects at its lower end with a channel 35 formed in the carburetor casting and a passage 36 communicating with a depression or gutter 37 formed in the lowest part of the air passage 21. The passage 36 is preferably smaller than the interior of the pipe 34 and channel 35 so that a relatively high velocity results at the entrance to thereby quickly draw the surrounding gasoline into the suction pipe. The upper end of the pipe 34 is shown connected with the intake conduit 12 at 38 so that it is always subject to the suction of the motor, and, therefore, when the throttle valve 16 is nearly closed, as for idling, there will be a high suction in this pipe 34 and whatever particles of fuel may collect in the depression 37 will be carried through this pipe around the combustion device and directly to the motor intake conduit. This will slightly increase the richness of the mixture passing to the motor, but the operation of the combustion device will not be interfered with because of the less rich mixture it will receive, and

its continued operation will assist in vaporizing the heavier mixture and thus aid in maintaining even running of the motor.

A specific embodiment of the invention has been described in detail and will be specifically claimed, but it will be understood that the invention is not limited to the exact details of construction shown, as it will be apparent that changes may be made without departing from the spirit or scope of the invention.

Having thus described my invention, what I claim and desire to secure by Letters Patent is:

1. In a hydrocarbon motor, the combination with the intake conduit thereof, a carburetor connected to said conduit, and a suction operated combustion device connected to draw its mixture from said carburetor and discharge into said conduit, of a suction pipe extending from a part of said carburetor where heavy fuel collects during idling of the motor, to said conduit.

2. In a hydrocarbon motor, the combination with the intake conduit thereof, a carburetor connected to said conduit and having main and auxiliary air passages, and a suction operated combustion device connected to draw its mixture from said carburetor and discharge into said conduit of a suction pipe extending from the bottom of said auxiliary air passage around said combustion device to said intake conduit.

3. In a hydrocarbon motor, the combination with the intake conduit thereof, a carburetor connected to said conduit, and a combustion device having its intake for mixture connected to said carburetor, of a suction conduit extending from a low part of said carburetor around the intake of said combustion device to said intake conduit.

4. In a hydrocarbon motor, the combination with the intake conduit thereof, a carburetor connected to said conduit, and a combustion device having its intake for mixture connected to said carburetor, of a suction conduit extending from a part of said carburetor where heavy fuel collects during idling, around the intake of said combustion device, to said intake conduit.

5. In a hydrocarbon motor, the combination with the intake conduit and a throttle valve therein, a carburetor connected to said conduit, and a combustion device connected to draw its mixture from said carburetor before the mixture reaches said throttle valve, of means for carrying any heavy particles of fuel collecting in the carburetor around the combustion device to the intake conduit beyond the throttle valve.

6. In a hydrocarbon motor, the combination with a carburetor having an extension forming a motor intake conduit, of a combustion device having its intake connected to said carburetor, and a suction conduit

extending from said carburetor to a part of whereby said carburetor supplies a suitable said intake conduit beyond the intake of mixture to said combustion device and a said combustion device. richer mixture to the motor. 10

7. In a hydrocarbon motor, the combination with a carburetor connected thereto, and a combustion heater device adapted to withdraw mixture from the carburetor, of means In testimony whereof I affix my signature.

JESSE G. VINCENT.
